United States Patent Office

Des. 218,411
Patented Aug. 18, 1970

218,411

BUILDING

Peter S. K. Yeung, Atlanta, Ga., assignor to Wellington Hall, Ltd., Thomasville, N.C., a corporation of North Carolina

Filed Aug. 11, 1969, Ser. No. 18,637

Term of patent 14 years

Int. Cl. D25—04

U.S. Cl. D13—1

FIG. 1

FIG. 2

FIG. 3

FIG. 4

FIG. 5

FIG. 1 is a front view in elevation of a building showing my new design;

FIG. 2 is a left-hand side view in elevation of the building of FIG. 1;

FIG. 3 is a top plan view of the building of FIG. 1;

FIG. 4 is a rear view in elevation of the building of FIG. 1; and

FIG. 5 is a perspective view of the building of FIG. 1.

The undisclosed right-hand side of the building is a mirror image of the left-hand side shown in FIG. 2.

I claim:

The ornamental design for a building, substantially as shown and described.
